(57) **CLAIM**

The ornamental design for a hot air comb, as shown and described.

DESCRIPTION

FIG. 1 is a front, left, and bottom perspective view of a hot air comb, showing our design.

FIG. 2 is a rear, right, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of the area labeled "9" in FIG. 1; and,

FIG. 10 is a partial enlarged view of the area labeled "10" in FIG. 1.

The dashed broken-lines shown in the drawings are included for the purpose of illustrating portions of the hot air comb that form no part of the claimed design. The long-short-long broken-lines indicate the bounds of the areas in FIG. 1 (that are shown enlarged in FIGS. 9 and 10), and illustrate the bounds of the enlarged views. The long-short-long broken lines form no part of the claimed design.
